(57) **CLAIM**

The ornamental design for a vegetable grater, as shown and described.

DESCRIPTION

FIG. 1 is a first perspective view showing a first part of the vegetable grater showing my new design;
FIG. 2 is a second perspective view of the first part of the vegetable grater;
FIG. 3 is a front view of the first part of the vegetable grater;
FIG. 4 is a back view of the first part of the vegetable grater;
FIG. 5 is a left side view of the first part of the vegetable grater;
FIG. 6 is a right side view of the first part of the vegetable grater;
FIG. 7 is a top plan view of the first part of the vegetable grater;
FIG. 8 is a bottom plan view of the first part of the vegetable grater;
FIG. 9 is a first perspective view showing a second part of the vegetable grater showing my new design;
FIG. 10 is a second perspective view of the second part of the vegetable grater;
FIG. 11 is a front view of the second part of the vegetable grater;
FIG. 12 is a back view of the second part of the vegetable grater;
FIG. 13 is a left side view of the second part of the vegetable grater;
FIG. 14 is a right side view of the second part of the vegetable grater;
FIG. 15 is a top plan view of the second part of the vegetable grater;
FIG. 16 is a bottom plan view of the second part of the vegetable grater;
FIG. 17 is a first perspective view of the combined state of the first part and the second part of the vegetable grater; and,
FIG. 18 is a second perspective view of the combined state of the first part and the second part of the vegetable grater. The broken lines shown in the drawings depict portions of the vegetable grater in which the design is embodied that form no part of the claimed design.
The first part and second part, FIGS. 1-8 and 9-16 respectively, are shown separately for clarity of illustration.
